LIQUID FUEL DISPENSING PUMP

Roy Frederick Gray, Maidenhead, England, assignor to
Dresser Europe S.A., Brussels, Belgium

Filed Nov. 1, 1973, Ser. No. 411,861

Claims priority, application Great Britain May 3, 1973

Term of patent 14 years

Int. Cl. D20—02

U.S. Cl. D52—2 A

FIG. 1

FIG. 2

FIG. 5

FIG. 6

FIG. 1 is a rear perspective view of a liquid fuel dispensing pump showing my new design;

FIG. 2 is a front perspective view thereof;

FIG. 3 is a rear perspective view of another embodiment of my new design of FIG. 1 wherein the hose has been placed on the side panel;

FIG. 4 is a front elevational view of FIG. 3;

FIG. 5 is a rear perspective view of yet another embodiment of my new design of FIG. 1 wherein dual hoses have been placed on the rear panel; and

FIG. 6 is a front perspective view of FIG. 5.

I claim:

The ornamental design for a liquid fuel dispensing pump, substantially as shown and described.
